UNITED STATES PATENT OFFICE.

JULIUS MALTBY, OF WATERBURY, CONNECTICUT, ASSIGNOR TO WATERBURY BUCKLE CO., OF WATERBURY, CONNECTICUT, A CORPORATION.

GARMENT-FASTENER BUTTON.

1,418,819.

Specification of Letters Patent. Patented June 6, 1922.

Application filed December 7, 1921. Serial No. 520,473.

To all whom it may concern:

Be it known that I, JULIUS MALTBY, a citizen of the United States, residing at Waterbury, in the county of New Haven and

5 State of Connecticut, have invented a new and useful Improvement in Garment-Fastener Buttons; and I do hereby declare the following, when taken in connection with the accompanying drawings and the characters of reference marked thereon, to be a full, clear, and exact description of the same, and which said drawings constitute 10 part of this application, and represent, in—

Fig. 1 a view in front elevation of the lower end of a tape provided with my improved garment-fastener button.

Fig. 2 a similar view with the fastening-loop thereof removed.

Fig. 3 an edge view thereof.

20 Fig. 4 an enlarged view in vertical section on the line 4—4 of Fig. 2.

Fig. 5 a perspective view showing the two complementary threading members of the button detached and separated.

25 Fig. 6 a similar view of one of the modified forms which my improved button may assume.

My invention relates to an improvement in garment-fastener buttons, such as are 30 used in garter-clasps, stocking and hose-supporters, and kindred articles, the object being to produce a button of the character described of superior comfort and efficiency.

With these ends in view, my invention 35 consists in a garment-fastener button having a button-base provided with two upstanding, serrated, self-embedding prongs having pointed ends and an initially-solid, rubber button-head into which the said prongs are 40 forced and by the serrated edges of which it is held in place.

My invention further consists in certain 45 details of construction as will be hereinafter described and particularly pointed out in the claims.

In carrying out my invention, as herein shown, I employ two complementary, one-piece button-base parts 10, each having an elongated threading-opening 11, a curved outer edge 12, a straight inner end 13 and an integral, upstanding, headless, self-embedding prong 15 having serrated edges 16 and a pointed end 17. With such button-base

parts as described, I employ an initially-solid rubber button-head 18, into which the 55 two serrated prongs 15 are thrust, their pointed ends making their own way into the soft rubber in which their serrated edges are embedded, so as to effect the firm anchorage of the head upon the prongs, which, 60 however, are not deprived of a certain amount of relative movement, due to the elastic character of the head, so that the button-structure may respond in a measure to the strains which may be thrust upon it 65 in use.

If desired, the pointed ends of the prongs may be constructed as shown in Figure 6, in which they are given an arrow-shaped form 19, so as to overhang the serrated sides 70 of the prongs, the anchoring power of which is thus somewhat increased.

But I do not limit myself to forming the button-base parts or the self-embedding prongs thereof in any particular form, the 75 salient feature of my invention being the employment of a button-base having a plurality of self-embedding prongs adapted to be thrust into an initially-solid rubber button-head for the firm anchorage of the same 80 thereupon.

In the form of my improved button herein shown, the button-base parts 10 are additionally connected by the lower end of the tape or webbing 20, which is threaded 85 through their elongated threading-openings 11 and stitched as at 21. The wire loop 22 is mounted upon the webbing 20 in the usual manner and co-acts with the button-structure in the usual way, with the exception 90 that in the case of diagonal strains upon the loop 22, the same may act through the button-head 18 to effect a slight displacement of the button-base parts with respect to each other, so as to accommodate the 95 button to the direction of the strains, and thus improve its grip and minimize the danger of cutting the fabric.

I claim:

1. A garment-fastener button having a 100 button-base provided with two self-embedding, upstanding prongs, and an initially-solid, rubber button-head into which the said prongs are embedded for the anchorage of the button-head thereto. 105

2. In a garment-fastener button, the com-

bination with two complementary button-base parts, each having a threading-opening and an upstanding serrated, self-embedding prong formed with a pointed end, of an initially-solid, rubber button-head into which the said posts are thrust and in which they are held by their serrated edges, where-
5 by the head is anchored firmly to them.

In testimony whereof, I have signed this specification in the presence of two subscrib- 10 ing witnesses.

JULIUS MALTBY.

Witnesses:

CHESTER LITTLE,
MARTIN T. LYNN.
